UNITED STATES PATENT OFFICE.

ELLIS C. WINCHESTER, OF THERMOPOLIS, WYOMING.

DETONATING MECHANISM FOR NIGHT GUARDS OR ALARMS.

1,159,458.

Specification of Letters Patent.

Patented Nov. 9, 1915.

Original application filed March 25, 1912, Serial No. 686,141. Divided and this application filed August 17, 1912. Serial No. 715,648.

To all whom it may concern:

Be it known that I, ELLIS C. WINCHESTER, a citizen of the United States, residing at Thermopolis, in the county of Fremont and

5 State of Wyoming, have invented a new and useful Detonating Mechanism for Night Guards or Alarms, of which the following is a specification.

The present invention relates to improvements in detonating devices for night guards or alarms, the present application being a divisional application of an application filed March 25, 1912, Serial No. 686,141 (now Patent No. 1,055,687 issued March 11, 1913), 10 and its object being to provide a novel form of detonating means, whereby blank cartridges are exploded at predetermined intervals through the medium of a novel mechanism, the same combining with the flash light structure set forth in the above application a night guard or alarm which will retain sheep or other animals upon their bedding grounds while the detonating device will frighten away predatory animals 15 by giving the intermittent audible alarm.

A further object of the present invention is the provision of a novel form of cartridge carrying dial, and firing pin or detonating means, whereby the cartridges are placed in 20 firing pin registration one at a time, and are exploded through a spring motor controlled by an escapement.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

In the drawings—Figure 1 is a side elevation of the apparatus taken from the cartridge carrier or dial side thereof. Fig. 2 is a section taken on line 2—2 of Fig. 1 looking at the rear of the machine. Fig. 3 is a section taken on line 3—3 of Fig. 1 to clearly illustrate the position of the firing pin device. Fig. 4 is a sectional view through the plunger and firing pin mechanism. Fig. 5 is a section through the cartridge carrying dial and support for guiding the firing pin to the percussion cap, the section being 35 taken on the line 5—5 of Fig. 1. Fig. 6 is a

detail view of the shaft for actuating the firing pin. Fig. 7 is a detail elevation of a portion of the firing pin guiding dial.

Referring to the drawings, the numeral 1 designates the base of the frame of the apparatus, which has the upstanding framework 2, the same being covered and protected to withstand the elements so that the mechanism carried thereby will in no way be affected.

Journalized in the frame is a shaft 3, which has operably connected thereto a spring motor 4, the outer end of said shaft 3 being squared to receive a winding key for winding the spring motor 4.

Keyed upon the shaft 3 within the frame is a large gear 5, while also keyed upon said shaft 3 is a small gear 6. This gear 6 is in mesh at all times with a large gear 7 mounted upon a counter shaft 8 which is parallel to the shaft 3. Journalized for rotation upon the shaft 8 forwardly of the gear 7 is a sleeve 9, which has keyed thereupon the small gear 10 and the large gear 11, thus permitting the sleeve 9 to rotate upon the shaft 8. The gear 10 is in mesh at all times with the large gear 5, so that the sleeve 9 is rotated by the shaft 3 through the gear 5 and in turn rotates the gear 11. The gear 11 is in mesh at all times with a small gear 13 carried upon the counter shaft 14. The gear 15 is connected to the shaft 14 and is therefore consequently operated through the gears 11 and 13.

Upon the shaft 8 is keyed a small pinion 28, which is in mesh at all times with a large gear 29 carried upon the counter shaft 30 and upon this shaft 30 is a beveled pinion 31, meshing at all times with a pinion 32 carried upon the shaft 33. This shaft 33 is journaled in the frame and at right angles to the shaft 30. Upon the outer end of the shaft 33 is mounted a firing pin guiding dial 34, whereby the rotation of the shaft 33 will rotate the dial. Formed in the dial 34, at the desired distances are a plurality of circular cavities 36 for the reception of the base of the blank cartridges C, the apertures 35 being disposed in a line for the reception of the firing pin 48 to guide the same into engagement with the percussion cap. A plate or disk 51 is carried at the inner or rear side of the dial or disk 34, and is provided with apertures 50 registering with the apertures 35 of the dial or disk 34.

The plate or disk 51 is carried around with the dial 34 and shaft 8. Secured to the disk 51 by means of the hinge joint 37 is the cartridge carrying dial 38, which is provided with a plurality of apertures 39 for the reception of the breech block or casing 40, in which the cartridges C are removably inserted from the rear of the said dial 38. In order to lock the dial in assembled position, after the cartridges have been placed therein, a screw 41 with the thumb nut 42 is provided, the same forming a locking means whereby the dials may be rotated by the shaft 33 and have the caps of the cartridges presented at the proper time and in alignment with the firing pin 48. Keyed upon and rotatable with the shaft 8 beyond the gear 28, is a double arm 42, which is provided with two upstanding pins 43 disposed in the path to engage the trigger 44. This trigger 44 projects through the elongated slot 45 formed in the firing pin plunger supporting and guiding tube 46, as clearly shown in Fig. 4, and which is supported within the frame of the apparatus. Mounted for reciprocatory movement within the tube 46, is the firing plunger 47, carrying the firing pin 48, which as before stated, is disposed to be projected through the aperture 35 to engage the percussion cap of the proper cartridge C. In order to propel the firing pin after the trigger has been released, by one of the arms 43, the spring 49 is provided. As the arms 43 are carried by the shaft 8 the rotation of the shaft will impart movement to the arms 43, and thus moving the trigger 44 against the action of the spring and finally releasing the same to the propulsive action of the spring so that the pin 48 thereof will pass through the apertures 50 and 35 in the disks 51 and 34, respectively, and thus impinge the percussion cap of the cartridge. When the disks 38, 34 and 51 are rotated to bring one pair of aligning apertures 50 and 35 into alignment with the pin 48, the trigger 44 is moved to the right, as seen in Fig. 4, and is released to permit the pin 48 to enter the respective apertures 50 and 35, so as to violently engage the percussion cap of the respective cartridge. This will produce the desired flash and detonation.

In order to provide an intermittent actuation of the various devices by the motor and consequently stop and release the motor intermittently, a small gear 52 is in mesh at all times with the gear 15 and receives its motion therefrom, the gear 52 being keyed upon the counter shaft 53 and carrying the large gear 54. This gear 54 is in mesh with the small gear 55 upon the counter shaft 56, while this counter shaft 56 is extended rearwardly and above the shaft 30 in the center of the machine and is journaled in the bracket 57. Upon the extreme rear end of

the shaft 56 is a small bevel pinion 58, which meshes at all times with the bevel pinion 59, carried by the vertical shaft 60. This shaft 60 is properly supported in the frame of the apparatus and carries thereon the double arm 61, which has depending from the free ends thereof, the two flexible cords 62, upon whose lower ends are secured the weights 63. Connected to and depending from the top of the frame, are the two vertical rods 64, both of which are disposed in parallel and upon opposite sides of the shaft 60. By means of the arms 61 and the weighted cords 62 in combination with the two vertical and spaced rods 64, which are disposed to have the cords 62 intermittently wound and unwound thereupon and therefrom, an escapement or means for preventing the constant tendency of the motor 4 to rotate and to permit an intermittent stopping and releasing thereof, is provided, this means constituting an escapement which permits the mechanism to be halted during the positioning of the cartridge to the firing pin and during the firing of the same, the cord 62 being wound first upon one post 64 and upon the next, the winding thereupon retarding the motor, while the release therefrom permits the motor to actuate the various mechanisms.

In order to properly support this apparatus to permit the same to be moved from place to place, the tripods 65 are connected by means of plates 66 to the upper portion of the supporting structure as clearly shown in Fig. 1.

It will be noted that the shafts 8 and 33 due to the escapement mechanism, are rotated intermittently and synchronously, so that the dial 38 is rotated and stopped simultaneously with the retraction and release of the firing plunger 47. Thus a new cartridge is positioned and halted just in time to receive the released firing pin. The shaft 56 controls the intermittent action of the motor 4, and consequently the shafts 8, 3 and 33, through the swinging weighted cords 62 and the rods 64, about which the cords wind due to the centrifugal force during the propulsion of the shaft 60, are permitted intermittent operation. Thus the period of winding and unwinding halts the shaft 56 and through the gears 52 and 15, and the shafts 8 and 30, the motor 4.

The operation of the shafts 8 and 30, is so timed that the cartridge dials are rotated through the shaft 30 and gears 31 and 32 and the shaft 33, so that the cartridge to be exploded is positioned and halted simultaneously with the release of the trigger 44 from one of the pins 43, the pin 48 passing a sufficient distance to fully retract and release the firing pin, so that when the firing pin is released through the action of its spring 49, the dial will have presented the

next succeeding cartridge and is held stationary during the exploding of the cap.

What is claimed is:

- In a detonating device for night guards or alarms, a frame, a spring motor mounted in the frame, a shaft rotated intermittently from the spring motor, two disks hingedly connected together at one point of their peripheries, the inner disk being fast to one 5 end of the shaft, said inner disk upon its outer face being provided with a plurality of cartridge base receptacles and a plurality of firing pin receiving openings, one opening leading concentrically from each receptacle through the disk, said outer disk having a plurality of cartridge receiving open- 10 15

ings therethrough, one to each base receptacle of the other disk, coöperating means carried by both disks to clamp the disks together to lock the cartridges in the openings 20 of the outer disk and their bases in the receptacles, and an intermittently actuated spring propelled firing pin for projection through the openings of the shaft actuated disk. 25

In testimony that I claim the foregoing as my own, I have hereto affixed my signature in the presence of two witnesses.

ELLIS C. WINCHESTER.
